ELECTRODE POSITIONING MEANS

Carl L. Fuller, Wellsville, N.Y., assignor to Apra Precipitator Corporation, New York, N.Y., a corporation of Delaware

Filed Nov. 17, 1958, Ser. No. 774,446
1 Claim. (Cl. 269—115)

This invention relates to electrostatic precipitators and more particularly to a portable fixture for concentrically positioning discharge electrodes of electrostatic precipitation apparatus within an outer collector surface.

The operation of electrostatic precipitation apparatus briefly comprises passing gas containing suspended foreign particles through a strong electric field between a centrally located discharge electrode and an outer grounded collector surface. The suspended particles become electrically charged and move, under the influence of a strong electric field, to the grounded collector surfaces. If any portion of the high voltage electrode is closer to the surrounding collecting surface, than any other portion, a situation will be presented where there will be a shunting or "flashover" at low voltage, thus limiting the strength of the field and the operating efficiency of the precipitator.

The primary object of this invention is therefore to provide means which will positively center each discharge electrode within a surrounding collecting surface to preclude flashover and provide an optimum of performance.

A further object of this invention is to provide an electrode centering device of a temporary nature that may be used repeatedly to provide economy of operation.

The above and other objects of my invention will become more apparent when viewed in the light of the following description of which the accompanying drawings are a part.

In the drawing FIGURE 1 is a perspective view, partly in section of my centering device as used to center a discharge electrode within a collecting tube.

FIGURE 2 is a plan view of my centering device as applied to an electrode within a hexagonal tube.

FIGURE 3 is a plan view of a single element that comprises my invention.

FIGURE 4 is a side elevation of the device of FIGURE 3.

In the drawings a series of collecting tubes 10 are disposed in abutting relation to provide a bank of collecting surfaces through which a flow of dust carrying gases is directed. Each tube is provided with a discharge electrode 12 that is positioned axially therethrough in the manner shown in FIGURE 1, and each discharge electrode is preferably formed with sharp projections or tab-like elements 14 that promote the electrostatic discharge to the surrounding surface 10.

In order that "flashover" may be precluded and the electrostatic discharge from the tabs may be maintained constant, it is necessary that the distance from the edge of each tab to the surrounding collecting surface be kept constant throughout the extent of the electrode. In accordance with this requirement, my invention provides a centering device or fixture that positively locks each electrode at the center of the tubular collecting surface until it may be permanently secured in such position by any

2

of various arrangements. After the electrodes have been permanently secured in position, the centering device or fixture may be readily removed for continued reuse.

The centering device comprises essentially two disks 16 each having an outside diameter only slightly less than the diametric distance between flats of a standard hexagonal collecting tube 10. Each disk is provided with a radial slot 18 adapted to embrace the discharge electrode 12 with the base of the slot contacting the side of the electrode when it is exactly centered, and each disk is provided with a lifting means or handle 20 on its face that extends axially thereof to facilitate insertion and removal from the end of a collecting tube.

In use the slot of each disk is adapted to slide around the discharge electrode 12 and into the hexagonal collecting tube 10 until it abuts the top discharge tab 14 on the electrode. The first such disk is inserted into an end of the collecting tube and around the discharge electrode as above specified before a second disk is superposed with its slot circumferentially displaced sufficient to provide a composite annular member with a central opening whose wall contacts the electrode to center it. In the form disclosed each disk is provided with a lifting means 20 secured to its upper face diametrically opposite the slot, whereby the lifting means of the lower disk extends through the slot of the upper when the slots are diametrically disposed. When the second disk is positioned within the hexagonal tube as above defined, the electrode is locked concentrically within the collecting surface and may be permanently secured as desired. After the discharge electrode is so secured, the centering disks may be readily removed by means of the handles 20 secured to the upper surface thereof.

While this invention has been described with reference to the embodiment illustrated in the drawing, it is evident that minor changes may be made without departing from the spirit of the invention, and it is intended that all matter contained in the above description or shown in the accompanying drawings shall be interpreted as illustrative and not in a limiting sense.

40 What I claim is:

Means for temporarily positioning a cylindrical discharge electrode coaxially within a regular polygonal collecting surface comprising, a pair of diametrically slotted positioning disks arranged in face-to-face engagement with their diametric slots opening in opposite directions to provide a composite annular member surrounding the discharge electrode, said disks having an outer diameter somewhat less than the distance between sides of the polygonal collecting surface; and a protuberance extending axially and in the same direction from the face of each disk adapted to permit their insertion into the collecting surface and around the discharge electrode in a plane normal to the longitudinal axes of said electrode.
